TANK UNIT WITH INTERNAL PUMP AND VALVE

Herbert H. Schmiel, Cleveland, Ohio, assignor, by
mesne assignments, to The New York Air Brake
Company, New York, N. Y., a corporation of
New Jersey

Application October 23, 1946, Serial No. 705,051

19 Claims. (Cl. 103—3)

1

This invention relates to packaged hydraulic units of the combined pump, control valve and tank type, and more particularly to such units where both the pump and valve are submerged in the liquid in the tank which is used for operating the hydraulic system.

It is a general object of the present invention to provide a novel and improved pump, valve and tank unit assembly of the type described.

More particularly it is an object of the invention to provide, in a unit assembly of the type described, an extremely simplified arrangement for reversing the pump passages to permit of reversal of direction of rotation of the pump.

An important feature in connection with the above object resides in the construction of the pump with one of its end plates constituting an essential portion of one of the side walls of the tank, with the pump and side wall portion symmetrical about vertical and horizontal axes, whereby the pump end-cover plate may be rotated 180° in its plane to reverse the passage connections and hence the direction of operation of the pump gears for coordinating the system.

Another important feature of the invention consists in the mounting of the "hoist and lower" valve beneath the lid or cover plate of the tank and in arranging for its connection to the pump discharge passage, to hoist ports in the cover and for the discharge of return liquid to improve the cooling operation of the whole system.

A feature in connection with the last mentioned object resides in so returning the liquid from the hoist, or from the pump discharge, to the valve manifold and the delivery of the liquid from this manifold beneath the liquid level in the tank and against one of the outer walls thereof to improve the heat transfer from the liquid to the atmosphere.

Another object of the invention consists in the complete assembly on the tank cover of the valve housing, its plunger and the operating means for the plunger permitting removal of the whole as a unit for service or inspection.

Other and further features and objects of the invention will be more apparent to those skilled in the art upon a consideration of the accompanying drawings and following specification wherein is disclosed a single exemplary embodiment of the invention with the understanding that such changes and modifications may be made therein as fall within the scope of the appended claims without departing from the spirit of the invention.

In said drawings:

Fig. 1 is a front elevation of the assembled tank unit including the pump, the control valve and the removable cover, a portion of the unitary tank wall and other parts being broken away to better illustrate certain internal features;

2
Fig. 2 is a side elevation, with parts of the side wall of the tank broken away to illustrate the pump arrangement and the valve location and with portions of the pump and valve housings in vertical section;

Fig. 3 is a top plan view of the assembly illustrating the alternative "hoist" ports at two edges of the cover;

Fig. 4 is a fragmentary vertical section taken on line 4—4 of Fig. 1; and

Fig. 5 is a fragmentary vertical section taken on line 5—5 of Fig. 3 and showing the valve housing and valve plunger only.

Hydraulic systems for the operation of simple hoists or rams have developed over a period of years and are in common usage now, particularly in connection with internal combustion engines as mounted on tractors or similar devices, for the manipulation and control of agricultural, earth moving or other attachments or implements. Such tractors and their power units vary considerably in construction and arrangements and particularly where remotely acting power take-offs are used for driving the pump of the hydraulic system. The principal differences reside in the direction of rotation of this take-off. This complicates the installation problem if there is no simple way to rearrange the piping to permit the pump to be driven in the direction required by the power takeoff. In the earlier systems where the pump, tank and control valve were individual units separately mounted and piped into the system, no complications occurred, since the mere transfer of the inlet and discharge pipes of the pump solved the whole problem. With the advent of the packaged unit, in which the whole system except the hoist and its connecting pipes is assembled into a single structure, the problem of reversible pump rotation added a considerable complication. The present invention contemplates a pump and valve both submerged in the tank and provides for a simple method of reversing the direction of rotation of the pump and the direction of movement of the fluid from it without requiring any changes in the tank, pump, piping or the control valve. No external piping is used and substantially all ducts, passages or the like are cored into the castings for simplicity and economy of manufacture.

Referring now to the drawings, for a better understanding of the invention, it will be noted that the tank 10 is a unitary casting, and is substantially rectangular in plan, elevation and end view. The cover 12 is a separate casting generally convex in form and meeting the top of the tank in a horizontal peripheral surface 14 appropriately gasketed to prevent leakage. Substantial fastening members 15 pass through holes in the edge of the cover and are threaded into reinforcements on the inner rim of the wall of the tank for holding the parts securely and ac-

curately together for a purpose which will presently appear.

As seen in Fig. 2, the rear wall 16 of the tank is substantially flat and vertical; the bottom wall 17 is flat and horizontal, while the front wall is broken and includes an upper broad, flat vertical portion 18, a horizontal offset portion 19 and a vertical portion 20 inset somewhat from 18. The portion 20 is a removable plate substantially rectangular in form, as seen in Fig. 1, and closing an opening in the lower side of the tank only slightly less in dimensions than the overall size of the cover. A suitable gasket applied between the plate and the rim of the opening insures a fluid tight connection and appropriate sturdy fastening means 21 securely attach the plate to the side of the tank.

The plate 20 is in effect an integral enlargement of the cast end flange of a housing for a pump device which includes the main body part 23 and the rear cover plate 24. As seen in dotted outline in Fig. 1, the pump is of the two gear type and of generally conventional form, having the lower or drive gear 26 and the upper or driven gear 27 pocketed in appropriate chambers in the main housing. At the junctions of these chambers are formed intake and discharge pockets 28 and 29, merging respectively into curved passages 30 and 31 symmetrically arranged as seen, the inlet one shown ending in a counterbore 33 with the opening near the bottom of the tank while the other ends in a counterbore 34 with the passage opening directly upwardly near the right side of the tank. Both inlet and discharge openings are accurately machined to selectively receive a fitting, as will be later described. As seen in Fig. 2, the drive gear 26 is arranged to be driven directly by splined shaft 35, which when in the lower position, shown, must be driven counterclockwise, as viewed in Fig. 1, to insure discharge through passage 31. This shaft is adequately journaled in a bearing extension 36 integral with the plate 20 and terminating in a wide mounting flange 37 drilled as shown to receive attaching studs for supporting the whole tank unit from its parent machine.

If the prime mover is of the type requiring clockwise rotation of the pump drive gear, then this is readily achieved by removing the cover plate 20 and its attached pump and rotating it 180° in its own plane and remounting. The cover plate and pump mounting are symmetrical about the horizontal axis 38 and about the vertical axis 39 so that when the position is changed as just described the discharge outlet 34 becomes the inlet and vice versa. The spline drive shaft and its mounting flange move up to a higher position as shown in dot and dash lines in Fig. 2, but otherwise the unit is similar in appearance to before the change.

Either of the pump counterbores 33 or 34, when positioned in the upward position, is adapted to receive with a press or other suitable sliding fit a discharge tube or pipe 40 leading vertically upwardly and having a suitable fit in the inlet port 41 in the control valve housing 43. This housing is a unitary casting having hoist ducts in appropriately surfaced bosses 44 for cooperation with oppositely directed depending bosses 45 in the lid or cover 12, whereby the two may be secured together by suitable fastenings 46 and fluid tight joints between passages and ducts in the two parts be provided as will later appear. The meeting surfaces of the bosses are in the same plane as the cover rim for ease in

machining. The valve housing 43 is thus supported in horizontal position just beneath and from the cover and may be removed with the cover by the mere separation of the pressed fit at 34.

The valve may be any of the recognized "raise and lower" valves, such as used for the control of single or double acting hydraulic cylinders. The valve shown is of the type disclosed in the 10 application of Hall Kirkham, Serial No. 695,680, filed September 9, 1946, now Patent 2,448,532, granted September 7, 1948, with suitable modification to adapt it for use in the present unit. These modifications include the lateral extension 15 48 of the high pressure inlet chamber 47 which has its bottom wall vertically bored as at 41 to receive the coupling pipe 40, previously described.

Immediately below the chamber 47 and connected thereto is a cartridge type relief valve 20 50, seen in Fig. 4. It is provided with an accurately machined nipple 51 threaded into a bore 52 in the wall of the valve housing beneath chamber 47 and is fitted with a gasket at 53 where it enlarges in diameter and a sealing ring at 53'. 25 The valve plunger 54 is pressed by spring 55 against seat 56 to be lifted only when excess pressure occurs in 47, when liquid lifts the valve and flows through the bore in the seat into radial passage 57 leading to low pressure manifold 58 forming an integral part of the valve housing as 30 seen in Figs. 1 and 5. This manifold also receives the discharges from the low pressure relief valves, such as shown at 60, which maintain pressure in the end chambers 62 and 63 of the valve 35 housing for holding the control plunger 100 in either of its hoist positions as defined in the Kirkham patent. The manifold 58 also takes the pump discharge from passage 64 during the time that the valve plunger is centralized so as to 40 freely by-pass all of the liquid from the pump which enters the plunger bore through spaced ports 101. The manifold 58 discharges into an oblique fitting 66 extending from its bottom wall and a discharge tube 67, which is inclined downwardly and has clipped end 68 closely adjacent to the side wall of the tank whereby the circulated and returned liquid is directed against this wall to permit improved heat transfer to the atmosphere to maintain the liquid at a suitable 45 low temperature under all conditions of operation.

The dished hollow cover 12 for the tank not only supports the control valve housing 43 but provides also the external outlets for the hoist 55 ducts of the valve whereby pipes may be connected to lead to a hoist unit for handling the liquid for actuating the same. As viewed in Fig. 3 the cover is provided on the left and lower edges with outwardly facing bosses 70, 71, 72 and 60 73, cast integrally with the cover and raising the thin edges at these portions to the maximum height of the cover as seen in the upper left in Fig. 1. Each of these bosses is drilled as shown and internally threaded to receive a pipe leading to a hoist. The hoist bosses are provided in pairs, thus 70 and 73 are arranged for alternative use, as are 71 and 72. This permits piping to run in either of two directions conveniently. The unused boss ports are plugged. It will be seen that cast integral with the lid is an internal, angled duct 74 connecting the bores of bosses 70 and 73 and having direct internal connection with a duct in the boss 45 to the right and on the under surface of the lid, which cooperates 65 75 with the corresponding duct in the top face of

the control valve housing. In a like manner the right angled duct 75 connects the bores of bosses 71 and 72 and the duct of the corresponding boss 45 on the under side of the cover. In Figs. 1 and 5 is seen at 76 a recess in each of the bosses 44 for receiving sealing rings to insure fluid tight connections between the abutting bosses on the under side of the cover plate and those on the top face of the valve housing.

The valve housing contains a controlling valve plunger 100, having an extension 80 passing through the left end of the housing 43, as seen in Fig. 5. This is provided with spaced fingers 81 between which is journalled a roller 82 by means of pin 83. A rotatable stub shaft 84 is journalled in a vertical bore in an appropriate bushing 85 in the tank cover and has an upper end 86 extending beyond the cover surface for engagement by a suitable lever and linkage means for manipulating the valve. Within the tank this stub shaft 84 is fitted with a lever 87 having a forked end, the furcations 88 of which closely straddle the roller 82 so that a partial rotation of stub shaft 84 serves to reciprocate the valve plunger to any of the desired manipulative positions thereof.

The operation of the control valve will be clear from Fig. 5. In the central position shown liquid from the pump enters through 101 and passes through grooves 102 in the plunger to 64 and 57 to the tank so that the pump is not loaded. If the plunger is moved to the left or right so that its central land 103 closes the corresponding passage between 101 and 64 then the end land on the plunger closes the similar passage on the other side. Liquid from the pump then flows in through the proper ports 104 in the plunger wall, lifts the check valve 105 and flows out the plunger ports 106 in register with power port 107 to actuate the hoist. Fluid from the opposite side of the hoist returns to the other power port 107 and around the end of the end land, which has moved toward the center, to fill the end chamber 108 of the valve housing. As long as this return liquid flows it exerts a sufficient pressure on the end of the valve plunger or on the annular area 109 thereof to oppose the action of the plunger centering spring 110 and the plunger is held in operating position. The returning liquid presses open appropriate plunger 112 against its spring and escapes to the return duct 58. When return liquid ceases to flow valve 112 closes and the chamber 108 is drained through seepage port 113 so that the centering spring returns the valve plunger 100 to the neutral position closing the power ports and locking the hoist in its set position. Movement of the plunger 100 in the opposite direction reverses the operation.

A convenient filler pipe 90 is shown bolted against the rear face 16 of the tank by means of a flange 91 and studs 92. This is equipped with an appropriately vented cap 93.

I claim:

1. A tank, pump and control valve unit for use with a hydraulic hoist comprising in combination, a tank for holding hydraulic liquid, a removable wall for said tank symmetrically arranged to be applied to the tank in either of two positions, a rotary pump mounted on said wall for submersion in the liquid in the tank and having an operating shaft extending through said wall, symmetrically disposed ported passages on said pump and each usable as inlet or discharge dependent on the direction of rotation of the said

shaft, a control valve mounted independent of said wall submerged in the liquid in the tank and having an inlet port, and means to automatically connect said inlet port to one or the other of said ported pump passages dependent on the position of mounting of said removable wall on the tank whereby either direction of pump rotation may be effective to supply said valve.

2. The unit as defined in claim 1 in which the removable wall is a side wall.

3. The unit as defined in claim 1 in which the removable wall is a side wall, a removable cover for the tank and means mounting the control valve on the inner face of said cover.

4. In a unit of the type defined, in combination, a tank for hydraulic liquid, a rotary pump submerged in the liquid and having a shaft passing through a wall of the tank, an inlet duct and a discharge duct for said pump interchangeable in use when the shaft rotation is reversed, a control valve in the tank having an inlet tube adapted for direct cooperative engagement with the active discharge duct of the pump, and means mounting the pump for change in position to engage the active discharge duct the cooperative engaging valve part to coordinate with direction of pump rotation.

5. In a unit of the type defined, in combination, a tank for hydraulic liquid, a rotary pump submerged in the liquid and having a shaft passing through a wall of the tank, an inlet duct and a discharge duct for said pump interchangeable in use when the shaft rotation is reversed, a control valve in the tank having an inlet tube adapted for direct cooperative engagement with the active discharge duct of the pump, a discharge tube for said valve extending within the tank to discharge against a side wall thereof, means mounting the pump for change in position to engage the active discharge duct the cooperative engaging valve part to coordinate with direction of pump rotation, and means to conduct valved liquid through a wall of said tank for external use.

6. In a unit of the type defined, in combination, a tank for hydraulic liquid, a rotary pump submerged in the liquid and having a shaft passing through a wall of the tank, an inlet duct and a discharge duct for said pump interchangeable in use when the shaft rotation is reversed, a control valve in the tank having an inlet tube adapted for direct cooperative engagement with the active discharge duct of the pump, means mounting the pump for change in position to engage the active discharge duct the cooperative engaging valve part to coordinate with direction of pump rotation, means to conduct valved liquid through a wall of said tank for external use, and means extending through a wall of the tank for actuating said control valve.

7. In a unit of the type defined, in combination, a tank for hydraulic liquid, a rotary pump submerged in the liquid and having a shaft passing through a side wall of the tank, an inlet duct and a discharge duct carried by and extending from said pump and interchangeable in use when the shaft rotation is reversed, said wall being removable and mounting said pump, the wall being symmetrical about central vertical and horizontal axes to permit of 180° rotation in the plane of the wall, said ducts having symmetrical outlets displaced 180° whereby the one acting as discharge may be positioned upwardly while the inlet is positioned near the bottom of the tank.

8. The unit as defined in claim 7 in which the removable wall is a substantially vertical wall,

a removable top cover plate for the tank, a control valve for the pumped liquid, means mounting said valve on and beneath the said cover plate, ports in said cover plate and integral passages in the cover plate connecting said ports to said valve.

9. The unit as defined in claim 8 in which the valve is fitted with a depending inlet pipe disposed near a wall of the tank which abuts said vertical wall, said pump ducts being so offset that the outlet of the discharge duct cooperates with said inlet pipe.

10. In a unit of the type described, in combination, a tank for hydraulic liquid, a reversible rotary type pump submerged in said liquid near the bottom of said tank, at least a portion of one side wall of said tank being removable, means mounting said pump on said wall, a shaft for said pump extending through said wall, fastenings securing said wall to said tank, said wall and the fastening disposition being symmetrical about 90° axes through the center of the wall whereby the wall may be applied to the tank in either of two positions 180° displaced in the plane of the wall, and two passages for said pump each having a terminal port, said ports being symmetrically disposed in respect to said axes.

11. In a unit of the type described, in combination, a tank for hydraulic liquid, a reversible rotary type pump submerged in said liquid near the bottom of said tank, at least a portion of one wall of said tank being removable, means mounting said pump on said wall, a shaft for said pump extending through said wall, fastenings securing said wall to said tank, said wall and the fastening disposition being symmetrical about 90° axes through the center of the wall whereby the wall may be applied to the tank in either of two positions 180° displaced in the plane of the wall, two passages for said pump each having a terminal port, said ports being symmetrically disposed in respect to said axes, a second removable wall for said tank, a control valve mounted on said second wall within said tank, an inlet passage for said valve, a tube extending from said passage and engaging with the pump terminal port positioned for the purpose and means to actuate said valve extending through said last mentioned removable wall.

12. The unit as defined in claim 11 in which the second removable wall includes integral ducts for conducting liquid from the valve to external circuits.

13. The unit as defined in claim 11 in which the first removable wall is a side wall and the second is the top of the tank, the pump ports being directed up and down respectively, the downwardly directed port extending close to the bottom of the tank.

14. In a tank, pump and valve assembly, in combination, a closed tank, a removable cover for the tank, a pump secured to the tank and adapted to pump liquid therefrom, a manually operable control valve unit mounted on the inside of the cover, separable means connecting said pump and said unit to handle all the liquid delivered by said pump, said unit adapted to discharge by-passed liquid, relieved liquid and liquid returned thereto at low pressure to said tank for reuse, a manifold on said valve unit to collect all of said liquid to be discharged, a delivery pipe receiving said liquid from the manifold, said pipe being arranged to deliver said liquid below the level of that in the tank and directly against a side wall thereof to increase the rate of cooling of the liquid.

15. The arrangement as defined in claim 14 in

which the pump inlet is remote from said delivery pipe outlet.

16. A tank and pump assembly including in combination, a tank, one side of said tank including a lower wall and an offset overhanging upper wall, said lower wall being removable and adapted to be received in either of two positions on the tank 180° displaced, a reversible rotary pump mounted on the inner face of said removable wall and having a shaft extending normally through the wall, a hub surrounding the shaft outside of and integral with the wall, a mounting flange on said hub to support the assembly, and the pump having two symmetrical passages 180° displaced adapted to be interchangeably inlet and discharge dependent upon the direction of rotation of the pump.

17. A tank and pump and valve assembly including in combination, a tank, one side of said tank including a lower wall and an offset overhanging upper wall, said lower wall being removable and adapted to be received in either of two positions on the tank 180° displaced, a reversible rotary pump mounted on the inner face of said removable wall and having a shaft extending normally through the wall, a hub surrounding the shaft outside of and integral with the wall, a mounting flange on said hub to support the assembly, the pump having two symmetrical passages 180° displaced adapted to be interchangeably inlet and discharge dependent upon the direction of rotation of the pump, a valve mounted on the inner face of one wall of the tank and having an inlet duct having an end adapted to cooperate with the then active discharge of the pump.

18. In a tank, a pump and valve assembly in combination, a tank having at least one wall removably secured thereto and adapted to be applied in either of two positions, a reversible rotary pump unit in the tank and having two passages interchangeable as inlet and discharge dependent upon the direction of rotation of the pump, a control valve unit in the tank adapted to receive liquid from the pump and control its delivery to a point remote from the tank, a rigid connection from the active pump discharge to the valve inlet, said pump unit being secured to said removable wall whereby the said connection may be caused to cooperate with the other pump passage when the direction of pump rotation is to be reversed.

19. The assembly as defined in claim 18 in which the valve unit collects all liquid to be returned to the tank and a delivery pipe for said collected liquid arranged to discharge against a fixed wall of the tank.
